KEY CONTAINER

Dewey Hendrix, Akron, Ohio

Application April 3, 1944, Serial No. 529,256

10 Claims. (CL 70—456)

This invention relates to an improved type of key container. More particularly, it relates to a key container from which the keys are ejected and made ready for use by merely pressing a button. It includes the combination of a flashlight with a key container, so arranged that the flashlight is lighted as the keys are made ready for use.

There are many types of key containers on the market. With almost no exception, these containers are constructed in such a way that the owner is expected to employ both hands in opening the container, removing a key, and readying it for use. This is many times objectionable as, for example, where the owner returns home laden with packages or the like which must be set down to free both hands to unlock the door.

The ideal key container is one which is easily and quickly operated with one hand. The container of this invention is of that type. The keys are ejected from the holder and made ready for use by the action of a spring which is released by pressure on a button. In a preferred form of the invention the keys, in springing from the container, close the circuit of a flashlight battery which throws a spot on the keyhole into which a key is about to be inserted.

The invention will be described in greater detail in connection with the accompanying drawing, in which Fig. 1 is a side view of the key container with the keys extended, Fig. 2 is a section on the line 2—2 of Fig. 1, Fig. 3 is a side view of the container with the keys retracted into it, Fig. 4 is a side view of a double container, Fig. 5 is an end view of the slide which holds the keys, Fig. 6 is a side view of a combination flashlight and key container. Fig. 7 is a section on the line 7—7 of Fig. 6, and Figs. 8 and 9 are a plan and section of the releasing mechanism of Figs. 1—3 on an enlarged scale.

The key container is preferably made of a plastic material which may be transparent and may or may not be colored. It may be made of metal, etc., if preferred. It is composed essentially of an outer case 1 and a slide 2, shown separately in Fig. 5, which holds the keys, and slides in the outer case in such a way as to eject the keys for use and retract them back into the container. The keys are advantageously supported on the sleeve 3, which may be of metal. The sleeve is preferably threaded at each end to receive buttons 4, which are provided with the shoulders 4a which fit into the slide openings 5 on the two sides of the case 1. The shoulders 4a thus limit the movement of the slide.

The slide is held in the case by the latch or

dog 6, which fits over the sliding catch 7 and holds the slide 2 in the case 1 against the action of the spring 8. When the catch 7 is pressed in, the spring is released, the slide 2 springs up in the container, and the keys 9 are ejected from the top of the container and are ready for use. The top corners of the container 1 are rounded at 10, and the side of the container is cut down to the line 11 so that the keys may be moved through an angle of 180° from one side of the top of the container to the other. The edge 11 serves as a stop to prevent the keys from falling any farther than to a position about perpendicular to the general body of the container. When the owner is through using the keys, the simplest way of retracting them into the case is by placing a thumb on one of the buttons 4 and drawing the slide down with the thumb until the beveled top of the latch 6 pushes the slide back, and it snaps back to hold the latch and keep the slide 2 in place.

The latch 6 may have an enlarged base 6a which is embedded in the slide 2.

In the drawing the cylinder 13 and spring 15 act to hold the latch 6 and the slide 2 to which it is fastened against the action of the spring 8 and to release them as desired. The catch 7, which coacts with the latch 6, is a part of the cylinder 13. This cylinder 13 slides within the outer cylinder 14. Both cylinders are preferably made of metal. They are both cut away at the opening 16 to permit the latch 6 to enter them and be retained by the catch 7. The burr 17 on the inner cylinder prevents it from being ejected from the outer cylinder by the spring 15. The two cylinders are assembled before the ends of the inner cylinder are closed.

The cylinder 14 is held in place in any suitable manner, as by an adhesive or by molding the container around it. The parts may be assembled by inserting the cylinder into the bottom portion of the container through an opening at one end of the container through which the outer end of the cylinder 13 projects to serve as a release 45 button 18 to release the latch and permit the keys to be ejected from the case. The depression 19 in the case permits greater freedom of movement of the release button 18.

The cylindrical compartment at the bottom of 50 the container is separated from the rest of the outer case by the partition 20. The cylinder 21 erected on the partition 20 is somewhat smaller in diameter than the cylindrical opening 22 in the slide 2 and fits within it with enough space to spare around its circumference to comfortably

hold the spring 8. The cylinder 21 keeps the spring 8 in position when the slide is extended as in Fig. 1 and provides a support around which the spring 8 is coiled within the opening 22 when the slide is retracted in the case, as shown in Fig. 3.

Fig. 4 shows a double container, each side of which operates in the same manner as the individual container illustrated in Figs. 1-3. It comprises the two halves 25 and 26, each of which includes a slide and spring with latch-releasing means of a type identical with that previously described. This enables one to carry twice the number of keys that can be accommodated in a single container. Each side of the container may hold three or four keys, more or less, the number being variable. If a container is used to hold fewer than the maximum number of keys it can accommodate, washers may be placed on the sleeve to hold the keys upright.

It is a great convenience to have a spotlight directed on a keyhole at night, and the combination flashlight and key container shown in Fig. 6 provides for such a spot directed on the keyhole as the key is about to be inserted. The slide 2' is of the type already described, and the latch 6' operates in the manner already described. The key container and spring-held releasing means in Fig. 6 are throughout of the type described, except that a plate of copper 38 or other conducting metal is provided over the side of the slide 2' adjacent the flashlight. As the slide 2' is released and the keys 9' are ejected for use, the slide 30 makes an electrical contact between the points 31 and 32, completing the electrical circuit which lights the flashlight. The points 31 and 32 are connected to a spring of conducting material, as shown. The contact point 34 connected by a spring to the contact point 31 presses against the metal cover 35 of the flashlight battery 36. The contact point 37 connected by a spring to 40 the contact point 32 presses against the conducting socket 38 of the flashlight bulb 39 which is threaded into the support 40.

Now, as the button 18' is pressed, the slide 2' is thrown upward by the spring, presenting the 45 keys 9', ready for use. As the slide 2' moves upward, the contact bar 30 closes the circuit between the contact points 31 and 32, and the flashlight bulb is lighted. The light is directed toward the keyhole, and this aids the owner materially. After the door has been unlocked, the keys 9' are 50 returned to the container as above described by pulling on the button 4' with the thumb, and in doing so, the electrical contact is broken, and the light is extinguished.

It is not always desirable to have the lamp 39 light up, as when the container is used in broad daylight. Therefore, a sliding switch 45, shown in detail in Fig. 7, may be provided between the socket 38 of the flashlight bulb and the battery 36 although this switch may be omitted. The switch operates through the opening 46 in the wall of the container. It is composed of nonconducting material with a conducting portion 47 (Fig. 7). If the switch is pushed into the battery 65 so that the conducting portion 47 comes between the socket 38 and the battery 36, the bulb will light when the bar 30 contacts the points 31 and 32. If, on the other hand, the switch 45 is located so that a nonconducting portion comes between the lamp and the battery, the lamp will not light. The stops 48 limit the longitudinal 70 movement of the slide.

In order to guide the slide switch 45, it is preferably manufactured with a raised portion 49

5 on each side thereof so that the lamp socket 38 slides between the two raised portions, regardless of whether it is positioned on the conducting portion 47 or a nonconducting portion. The wall of the case may be indented at the switch 45, or (as shown) may be raised around the protruding ends of the switch to prevent unintentional movement of the switch.

10 The battery 36 is held against the switch 45 by the spring 50. The bottom end of the flashlight container is provided with a circular threaded cap 51 against which the spring 50 presses. This cap may be removed for replacement of the battery as required. The switch may easily be assembled by insertion through the openings 15 46 when the flashlight and spring are removed.

It is to be understood that the design and construction of the container and battery may be altered without avoiding the appended claims which define the invention.

What I claim is:

1. A key container which comprises an outer container with slide openings on each side thereof, a sliding portion on which the keys are mounted adapted to slide therein with buttons on each side of the sliding portion with collars thereon adapted to slide in said slide openings, a spring in the outer container acting against the slide with means for movably locking the slide in the container with the spring compressed.

2. A container with flashlight and a slide therein, the slide being adapted to hold the keys and carry them to the operating position, electrical conducting means on the slide, and contacts for operating the battery in a position to be contacted by said conducting means when sliding the keys to operating position.

3. A combination key container and flashlight battery in which the keys are mounted on a slide to one edge of which an electrical conductor is attached, a flashlight battery and socket for a lamp, a contact connected electrically with the battery and another contact connected with the socket, said contacts being arranged so that the conductor on the slide connects both when the keys are moved to operating position and so that the contact is broken when the slide is retracted.

4. A flashlight and key container combination which comprises a battery, a socket for a lamp to be operated by the battery, a slide to hold the keys, conducting means on the slide with contact points connected with the battery and socket, respectively, adapted to be closed by the conducting means when the keys are slid to the operating position, and between the socket and battery a switch, one operating portion of which is a conductor for electricity and another operating portion of which is a nonconductor of electricity.

5. A combination key container and flashlight, which latter includes a battery and lamp and switch for operating the same, a slide adapted to hold keys with means for holding it in the container against the action of a spring and releasing it to slide to an operating position, the switch being operated by the slide as it is moved by the spring from the one position to the other.

6. A key container which comprises an outer container with slide openings on each side thereof, a slide in the outer container with a support for the keys extending from one side of the slide to the other adapted to hold one or more keys with their tangs outward, the ends of the support passing through the side walls of the support and extending into the slide openings, a spring in the outer container acting against the

slide, means for locking the slide in the container with the spring compressed, and means for releasing the lock.

7. A key container composed of an outer case and a slide adapted for longitudinal movement therein, the slide being adapted to hold a number of keys with their tangs outward, the edges of the outer case and of the slide being cut away so that with the slide in the extended position the keys may be swung in the cut-away portion of the case and slide to be at right angles to the longitudinal direction of the container, a spring in the outer case pressing against the slide, a locking device for holding the slide against the action of the spring, and means for releasing the locking device so that the spring will push the sliding portion outwardly to said extended position.

8. A key container composed of an outer case and a slide adapted for longitudinal movement therein, a slide opening in each of the side walls of the outer case and running longitudinally thereof, a key support passing from one side of the slide to the other adapted to hold the keys with their tangs outward, the ends of the support passing through the walls of the slide and into the slide openings, a spring in the case acting on the slide to push it the length of the slide openings, concentric cylinders in the bottom of the outer case with registered openings in the cylindrical walls thereof, a dog on the bottom of the slide adapted to pass through said openings when the slide is retracted against the spring,

5 and a second spring pressing against the inner cylinder to hold said openings out of register, one end of the inner cylinder being exposed so as to be pressed against the action of the spring to bring the openings into register so as to release the dog and thereby allow the first-mentioned spring to push the slide.

9. A key container which comprises a compartment, a slide and spring within the compartment, the slide being adapted to move within the compartment both with and against the action of the spring, the slide holding a bar for stringing one or more keys, one end of the bar extending through a wall of the compartment to facilitate manual movement of the slide against the action of the spring, means for locking the slide with the spring compressed, and means for releasing the slide.

10 10. In combination a flashlight and a key container, in the container a slide for keys which is 20 adapted to be slid outward to bring the keys into operative position and to withdraw them into the container out of operative position, in the circuit of the flashlight a switch adapted to be closed 25 as the slide is moved to operative position and opened as the slide is withdrawn into the container, and a second switch in the circuit adapted for manual operation for closing the circuit when the container is to be used in the dark and opening the circuit when the container is to be used 30 in the light.

DEWEY HENDRIX.
